(57) **CLAIM**

(**) Term: **14 Years**

The ornamental design for a head rail for retractable covering for architectural openings, as shown and described.

(21) Appl. No.: **29/248,262**

DESCRIPTION

(22) Filed: **Aug. 7, 2006**

FIG. 1 is an isometric of the head rail of the invention with a retractable covering shown in dashed lines, which is included for illustrative purposes only and forms no part of the claimed design.

(51) **LOC (8) Cl.** **08-05**

FIG. 2 is an enlarged top, front perspective view

(52) **U.S. Cl.** **D8/377**

FIG. 3 is a top plan view.

(58) **Field of Classification Search** D8/377;

FIG. 4 is a left end elevation.

D25/119, 125; 160/330, 342, 345, 22, 29

FIG. 5 is a front elevation.

See application file for complete search history.

FIG. 6 is a bottom plan view.
